UNITED STATES PATENT OFFICE

LEO H. BRODRICK, OF NEW YORK, N. Y.

CONTAINER

Application filed November 11, 1926. Serial No. 147,763.

My invention relates to containers and refers particularly to containers suitable for the hygienic protection of face powders and powder puffs.

5 Containers adapted for containing powders to be applied to the human skin, as for instance, face powders, talcum powders, body powders and similar products, should be hermetically sealed in order to protect the 10 powder from contamination, preserve it in a dry condition, and protect it from leakage.

In addition, such containers should be of economic construction and so formed that the introduction of the powder therein and the 15 sealing of the package will require a minimum of operation.

Further, as a powder puff is essential in the application of such powders, the container should be so constructed as to carry a powder 20 puff in a similarly air tight and hygienic receptacle.

In addition to the above requirements, the powder puff and the powder must be ready of access by the user.

25 The above mentioned, and other, advantageous features are incident to the container of my invention.

Various means have been employed for the 30 production of containers of this character for the retention of a powder mass and a powder puff within one container, but their manufacture has been difficult and expensive due to the elements employed in their construction. Another serious objection to the generally employed containers is the large 35 number of operations incident to their filling and sealing, and this latter problem is of the greatest importance to the powder manufacturer or dealer, who is desirous of marketing his products in a container of the described 40 character.

My containers are manufactured and sold in an empty condition with the exception of a powder puff, to the powder merchant and 45 the latter introduces the powder and seals the package. It is evident, therefore, that a reduction of operations necessary in filling and sealing is of the greatest importance to the powder merchant.

50 In my device, as detailed later, the opera-

tion of filling with powder consists in introducing the powder into the open container and closing the opening.

It is to be noted that in the device of my invention a powder mass and a powder puff 55 are enclosed in separate air-proof hermetically sealed receptacles combined into one device, the puff and powder being readily obtained for powder application and that the container cover is not a part of either sealed 60 receptacle, thus allowing the removal of the cover without destroying the hygienic protection to the receptacle contents.

An examination of the accompanying 65 drawings will clearly indicate the economy of material incident to the manufacture of my device with the consequent maintenance of low labor cost.

In the accompanying drawings illustrating 70 modified forms of my device, similar parts are designated by similar numerals.

Figure 1 is a side view of one form of my device.

Figure 2 is a top view of Figure 1 partly 75 broken away for clearness of description.

Figure 3 is a development, or lay-out, of the several parts of Figure 1, with the cover removed.

Figure 4 is an enlarged cross-section 80 through the line 4—4 of Figure 2.

Figure 5 is a development, or lay-out, of the several parts of Figure 6.

Figure 6 is a fragmentary vertical cross-section of a modified form of my device.

The particular form of the device of my invention illustrated in Figures 1 to 4 of the accompanying drawings comprises a powder puff receptacle formed by the annular cardboard side 10, having a paper bottom 11 which extends over the side 10 and is affixed 85 to the outer face thereof and a transparent cellophane, or other flexible, top 12 which extends over the side 10 and is affixed thereto. There is thus formed a separate hermetically sealed puff receptacle.

A casing consists of the annular side 13 having a separate metal bottom 14 capable of attachment to the side 13 as explained later.

The puff receptacle is placed within the casing with the sides abutting and fixedly at- 100

tached thereto. The side 10 of the puff receptacle extends above the side 13 of the casing and a strip of paper 15 is fixedly attached to the outer face of the casing side 13 and the outer face of the puff receptacle side 10.

5 A sheet of decorative paper 16 is then attached to the outer face of the casing side 13.

There is thus formed a hermetically sealed puff receptacle to which is attached a powder receptacle open at the bottom.

10 The cover consists of the annular side 17 capable of placement upon the top of the casing side 13 and a domed top 18. Suitable papers 19, 20 are attached to the outer faces of the cover side 17 and the cover top 18.

15 My device, therefore, comprises three separate members:—a hermetically sealed powder puff receptacle to which is attached a downwardly extended casing side, the puff receptacle extending above the casing side; a bottom

20 for the casing and a cover for the device the side of which is capable of abutment upon the top of the casing side.

25 The operation of my device is as follows:—

The container manufacturer delivers the three separate parts to the powder manufacturer, with a powder puff 21 within the closed puff receptacle. The powder manufacturer inverts the device, places powder 22 within 30 the open powder receptacle formed by the puff receptacle bottom 11 and the casing side 13, places the metal bottom 14 in position across the powder receptacle opening, and crimps it to the side 13 as shown in Figure 4, 35 thus forming a hermetically sealed powder receptacle containing the powder. The cover is then placed in position. While I prefer a metal bottom 14, a bottom of other suitable material may be employed.

40 The operations of the powder manufacturer, therefore, consists simply in introducing the powder and affixing the bottom.

The modification of my device illustrated in Figures 5 and 6 is similar to that described 45 except as regards the means of bottom closure.

In this modification, the side 13 has a fixedly attached bottom 23 having an opening 24 therein, and a false, or inner bottom, 25 having an opening 26 therein of smaller diameter than the opening 24 is fixedly attached to the inner face of the bottom 23. A closure 27 is capable of closing the two openings 24 and 26.

55 In this modified form, the powder manufacturer introduces the powder through the openings 24 and 26, fixedly attaches the closure 27 and covers the bottom with the paper 28.

60 It will thus be seen that by simply introducing the powder into the powder receptacle and closing the opening, he obtains a container having two hermetically closed receptacles, in one of which is a powder puff and in the other of which is the powder.

65 I do not limit myself to the particular size,

shape, number, arrangement or material of parts as illustrated and described, as these are given simply as a means for clearly describing my invention.

What I claim is:—

1. In a container of the character described, in combination; an hermetically sealed puff receptacle comprising an annular side wall, a friable bottom fixedly attached to said side wall and an imperforate friable top fixedly attached to said side wall; a cardboard supporting casing side extending below the puff receptacle and attached thereto; a bottom to the casing; a strip of paper extending around the outer face of the puff receptacle side and attached thereto, said paper being extended over the upper edge face of said supporting casing and downwardly over a portion of the outer face of said supporting casing and attached thereto; and a cover for the device. 70

2. In a container of the character described, in combination; an hermetically sealed puff receptacle comprising an annular side wall, a friable bottom fixedly attached to said side wall and an imperforate friable top fixedly attached to said side wall; a cardboard supporting casing side extending below the puff receptacle and terminating below the top of said puff receptacle and attached directly thereto; a bottom to the casing; and a cover 90 for the device.

3. In a container of the character described, in combination; an hermetically sealed puff receptacle comprising an annular side wall, a friable bottom fixedly attached to said side wall and an imperforate friable top fixedly attached to said side wall; a cardboard supporting casing side extending below the puff receptacle and terminating below the top of said puff receptacle and attached thereto; a bottom to the casing; a strip of paper extending around the outer face of the puff receptacle side and attached thereto, said paper being extended over the upper edge face of said supporting casing and downwardly over a portion of the outer face of said supporting casing and attached thereto; and a cover for the device. 100

Signed at New York city, in the county of New York and State of New York, this 4th day of November, 1926. 110

LEO H. BRODRICK.
